UNITED STATES PATENT OFFICE.

AMARIAH AVERY, OF MANCHESTER, NEW HAMPSHIRE, ASSIGNOR, BY MESNE ASSIGNMENTS, TO DRAPER COMPANY, OF HOPEDALE, MASSACHUSETTS, A CORPORATION OF MAINE.

SPINNING-MACHINE.

1,168,237.

Specification of Letters Patent. Patented Jan. 11, 1916.

Application filed November 12, 1913. Serial No. 800,653.

To all whom it may concern:

Be it known that I, AMARIAH AVERY, a citizen of the United States, residing at Manchester, county of Hillsboro, State of New Hampshire, have invented an Improvement in Spinning-Machines, of which the following description, in connection with the accompanying drawing, is a specification, like characters on the drawing representing like parts.

This invention relates to improvements in stop mechanisms for spinning machines and particularly in that type of machine in which filling is spun upon a bobbin having an apertured or slotted barrel adapted to receive the finger of a feeler which controls the replenishing mechanism of an automatic replenishing loom. The bobbin used in that type of looms is provided with a recess or slot near the base, over which the filling is wound. The feeler finger of the replenishment controlling mechanism engages the yarn upon each forward movement of the lay and so long as the yarn remains upon the bobbin in the path of the feeler finger the replenishment mechanism will not be operated. When, however, the yarn is unwound so that the feeler finger will enter the recess or slot the replenishment mechanism will be operated to substitute a new bobbin for the exhausted one. In machines of this type the feeler finger is ordinarily placed in such position that it will enter the slot nearer the end farthest removed from the base of the bobbin and it is therefore desirable that the bobbin should be so wound that when unwound in the shuttle the portion of the slot into which the feeler finger enters will be exposed and the replenishment mechanism operated while a sufficient amount of yarn remains upon the bobbin to supply a pick of filling, thus obviating any likelihood of a short end of filling being laid or a miss-pick made which would result in a defect in the fabric.

One of the objects of the present invention is to provide a quick and accurate stop mechanism for spinning machines, upon which such bobbins are wound, which will arrest the machine with the lifter rail elevated so that when new bobbins are supplied they will be in position to receive the filling at the bottom and wind the same upwardly

upon the barrel over the feeler slot; so that when the bobbin is unwound in the shuttle 55 the outer end of the feeler slot will be first uncovered in the manner aforesaid.

Another object of this invention is to provide means whereby the operation of the stop mechanism will cause the disengagement of the means for actuating the stop mechanism and thereby restore said actuating mechanism to its normal position.

Other objects of the invention will be more fully set forth in the accompanying description and drawings and the following claims.

In the drawings: Figure 1 is a front elevation of a portion of a cap spinning machine embodying my invention; Fig. 2 is an end elevation of a portion of such machine 70 showing the stop mechanism and a portion of the means for actuating the same, the spinning mechanism being omitted; Fig. 3 is a detail elevation of a portion of the lever mechanism for operating the stop mechanism; Fig. 4 is a detail view of the belt shifting mechanism forming part of the stop mechanism, and Fig. 5 shows a bobbin having a feeler slot showing the first winding thereupon.

The spinning machine embodying this invention comprises end frames 1 and suitable cross beams 2 to form supports for the spinning mechanism. The bobbins 3 are guided upon a series of spindles 4 which are suitably secured in a horizontal spindle rail and project through a lifter rail 5, the bobbins resting upon whirls 6 which in turn rest on the lifter rail and are rotated by belts 7 passing around said whirls and over driving mechanism of the usual form. Caps 8 are supported upon the upper ends of the spindles 4 and the bobbins are raised and lowered relative to said caps by elevating and depressing the lifter rail in the usual manner. The up and down or traversing movement given to the lifter rail winds the successive layers of filling upon the bobbin building the same from the base of the bobbin or cop toward its apex or nose.

In the machine illustrated herein two sets of spinning mechanism are provided, one at the front and the other at the rear of the frame, and the lifter rails are raised and lowered by heart-shaped cams located near 105 opposite ends of a suitably driven shaft jour-

naled in bearings on the front and rear members of the frame.

The mechanism for causing the up and down movement of the lifter rail comprises 5 a reciprocating carriage 10 which is connected, in any suitable manner, not shown, to the lifter rail by chains 11, passing over suitable pulleys 12—13, to the ends of the lifter rods 14, which support the lifter rail. 10 The forward and backward movement of the carriage causes the lifter rods and consequently the lifter rails to be raised and lowered in the desired manner.

The means provided for reciprocating the 15 carriage to cause an upwardly and downwardly traversing movement comprises a frame 15 projecting downwardly from the frame of the machine having at its lower end an adjustable pivot 16 upon which an 20 oscillating arm 17 is mounted, the arm 17 being provided at its other end with means engaging the carriage and intermediate of its ends and upon the side opposite to the carriage with an adjustable member 18 provided 25 with an antifriction roller 19 which engages an arm 20, which is actuated by a heart-shaped cam 21 suitably driven in any desirable manner. The lever 20 is adjustably supported at its upper end upon a 30 pivot 22 mounted in a slot 23 and is provided with an antifriction roll 24 which affords a rolling contact between the cam 21 and the lever. The motion transmitted through the heart-shaped cam to the lever 35 17 by the mechanism above described is adapted to give the carriage a backward and forward movement of substantially uniform amplitude.

In order to provide for the progressive 40 downward movement of the lifter rail to properly build a filling wind upon the bobbin, means are provided whereby the carriage is advanced slightly (to the right in the mechanism illustrated) upon each reciprocation, thus progressively lowering the lifter rail and consequently raising the path of the filling upon the bobbin. This is accomplished in the present machine by a screw 30 which engages a nut or collar 31 45 carried upon the upper end of the arm 17, and which may be secured thereto in any suitable manner. The screw 30 is rotatably connected at one end with a lug 34 upon the carriage and at its other end slidably feathered in a bearing sleeve 35 of one of a train 50 of gears adapted to rotate the same.

In operation the filling yarn is led from the usual drawing rolls, not shown, downwardly beneath the cap 8 to near the base 60 of the bobbins. The mechanism is then set in motion and the yarn is first wound around the barrel of each bobbin near its base, and as the carriage moves forward is caused to wind up on the barrels of the

bobbins for a distance equal to the forward 65 movement of the carriage 10. Upon the backward movement of the carriage the lifter rail and the bobbins are raised and another winding is deposited. In the meantime the carriage has been brought forward 70 slightly by the rotation of the screw 30 so that the next traverse will begin at a point slightly higher, and will also end at a point slightly higher than the preceding winding. This action will continue until the bobbin 75 is wound at which time the lifter rail will be in its lowest position. When the bobbins have been completely filled the machine is stopped in order that they may be doffed and it is desirable that the mechanism 80 should be so arrested that when the carriage is returned manually to starting position (at the left) the lifter rail will be at the highest point of its traverse so that the filling winding will again commence at the 85 base of the bobbin barrel and wind upwardly in the manner aforesaid. In order to accomplish this result it is necessary that the mechanism be arrested when the apex of the heart-shaped cam is in contact with 90 the antifriction roll 24 of the carriage actuating lever 20, and in the preferred embodiment of the invention illustrated herein means are provided which are set in operation by the carriage when at the extreme 95 right, and the lifter rail at the lowermost point of its traverse, said means being adapted to complete their operation and arrest the carriage at the end of its traverse to the left, when the lifter rail is at its 100 highest point of traverse.

In the preferred embodiment of the invention disclosed herein the stop mechanism comprises a screw actuated belt shipper which is adapted to shift the belt from the 105 driving pulley of the spinning mechanism to a loose or idle pulley, rotation being imparted to the screw for this purpose by the falling of a weight, the support for which is withdrawn by the carriage when the lifter 110 rail reaches a certain predetermined position.

In Fig. 4 of the drawings a fast pulley 40 for driving the spinning mechanism and a loose or idle pulley 41 on the same shaft 115 are shown, the driving belt 42 being adapted to be shifted from one to the other by a forked shipper 43 mounted upon the ends of a rotatable shaft 44. The shaft 44 is journaled in suitable bearings in the frame, 120 not shown, one or both of which are provided with screw threads engaging similar threads upon the shaft 44. The shaft 44 is adapted to be rotated manually by a hand wheel 45 or automatically in a manner hereinafter to be described. Obviously rotation of the shaft in one direction will cause the screw to move the rod axially to shift the

5 belt from the fast to the loose pulley to stop the machine, while rotation in the opposite direction will cause it to shift the belt from the loose to the fast pulley to start the machine. By the mechanism disclosed herein the starting and stopping of the machine may be performed manually at any time without interference with the automatic stop mechanism.

10 The automatic stop mechanism comprises a gear 46 rigidly mounted upon the shaft 44, which engages a companion gear 47 mounted upon a shaft 48 upon which a drum 49 is mounted, said drum having an attached chain 50 which after passing around the drum 49 and over an idle directing roller 51 supports the upper end of a depending bar 52 to the lower end of which is secured a heavy weight 53 by a link 54, or in any 15 other suitable manner. A guide 55 which is secured to the frame embraces the bar 52 and controls it when the weight is dropped. The bar 52 is provided near its lower end with a shoulder 56 which is adapted to engage 20 a latch 57 which preferably rests upon said guide and serves to support said bar and weight while the spinning mechanism is in operation. To stop the machine the latch 57 is withdrawn from engagement 25 with the shoulder 56 permitting the weight 53 to fall, thus causing the rotation of the drum 49 through the chain 50 and the consequent rotation of the shaft 44 which by 30 its simultaneous endwise movement moves 35 the belt shipper from the fast to the loose pulley.

The latch 57 is slidably mounted at one end preferably upon the guide 55 and at its other end upon a bracket 58 which depends from the frame and may be provided with a shouldered portion 59 engaged by a spring 60 to force the end of the latch into engagement with the bar 52. The latch 57 is retracted to release the weight through a 45 bell crank lever actuated by the movement of the carriage 10 when the same reaches the predetermined point of advancement aforesaid. This bell crank lever comprises a shaft 61, journaled in a suitable bracket 50 62 carried by the frame and arms 63-64 disposed at substantially right angles to each other. The arm 64 is slotted near its end to engage a stud 65 projecting from a collar 66 carried by the latch bar 57. The 55 other arm 63 of the bell crank lever is loosely connected by a bolt or pin to one end of a draw bar 67 adapted to be actuated by the carriage. The draw bar 67 extends longitudinally of the machine and has an 60 offset 68 which permits its extension 69 to be journaled in a bracket 70 carried by the carriage 10. The extension 69 of the draw bar is provided with two collars 72-73 which are preferably adjustably secured

thereto by set screws and with a sliding collar 74 loosely mounted between the fixed collars 72-73. By reason of the adjustability of these collars the stop mechanism may be operated to arrest the machine with the lifter rail in any desired position, but they are preferably arranged to stop the machine with the lifter rail at the highest point of its traverse, as above described. The sliding collar 74 is adapted to be engaged by the shoulder 75 of a spring detent 76 which is secured to the bracket 70 upon the carriage 10. The fixed collars 72-73 are slabbed off at the top to permit the detent to pass over without engagement therewith. 65 70 75 80

In the operation of the spinning mechanism the carriage 10 is first brought manually to its extreme retracted position (at the left in the machine illustrated herein) at which time the lifter rail is in its most 85 elevated position. The spinning mechanism is then started and the carriage 10 reciprocated as above described, being at the same time advanced by the screw 30 as the bobbin is being built. During the progress of 90 advancement of the carriage the detent will pass over the collar 72 and strike the sliding collar 74 which it will force against the fixed collar 73 and upon further advancement will ride over the same so that the 95 shoulder 75 of the detent will engage the farther side thereof. Then upon the backward reciprocation of the carriage the sliding collar will be moved along the extension 69 of the draw bar until it abuts 100 against the fixed collar 72 and upon further movement of the carriage the draw bar will be retracted, the bell crank lever (63-64) rocked, and the latch 57 withdrawn, thus releasing the weight and thereby causing 105 the shipping of the driving belt from the fast to the loose pulley in the manner aforesaid.

It will be observed that the engagement of the detent 76 with the collar 74 occurs 110 when the carriage is at the extreme right and the lifter rail at its lowest point of traverse but that by reason of the lost motion due to the sliding of the collar 74 upon the draw bar the stop mechanism is not actuated until 115 the carriage 10 has nearly reached the opposite limit (to the left) of its reciprocation so that when the parts are arrested the lifter rail is in its highest position of traverse and the apex of the heart-shaped cam 21 120 in contact with the antifriction roller 24 of the operating lever 20. The bobbins are then doffed and the carriage ready to be shifted to its initial position to start the winding of a new set of bobbins. In order, 125 however, that the carriage may be retracted to starting position it is necessary that the shoulder 75 of the detent be released from

engagement with the collar 74, and it is desirable that means shall be provided whereby these parts will be automatically disengaged immediately upon the actuation 5 of the stop mechanism. The means for accomplishing this result as embodied in the mechanism disclosed herein comprises a lever 80 which is pivoted upon a lug 81 projecting from the end frame, said lever 10 being provided at its outer end with a depression 82 which is adapted upon the dropping of the weight 53 to receive a stud 83 projecting laterally from the bar 52. The opposite end of said lever 80 is offset, as at 15 84, and has secured to its end 85 by suitable oppositely disposed winged nuts 86—87, a depending rod 88 which terminates in an eye 89 which embraces the draw bar 67 adjacent to the offset 68. The draw bar 67 and 20 its extension 69 are substantially parallel but by reason of the offset 68 the bearings for the ends of these respective members are in different vertical planes so that when the rod 88 raises the portion of the draw 25 bar adjacent to the offset the extension 69 near the offset will be depressed. It therefore follows that when the weight is dropped the stud 83 will engage the depression 82 of the lever 80, depressing that end 30 of said lever and consequently raising the opposite end 86 and its depending rod 88 thus depressing the draw bar extension 69 and releasing the shoulder 75 of the detent from engagement with the collar 74 and 35 permitting the carriage 10 to be restored to its starting position.

It is to be understood that the apparatus herein described comprises one embodiment of my invention, but that it is illustrative 40 merely and that my invention may also be embodied in other forms of apparatus and also that its application is not restricted to its use in connection with spinning machines. It is also to be understood that the 45 stop mechanism embodying my invention not only comprises means whereby the machine may be arrested with the lifter rail at its highest point of traverse, which has been described as the preferred position, but 50 that said means are capable of such adjustment as to arrest the machine with the lifter rail at any predetermined elevation which may be found to be desirable. For example, if bobbins are being wound which 55 are to be used upon exceptionally wide looms, it may be found that a single winding from the base of the bobbin upward over a portion of the feeler slot will not be sufficient for a pick. In such case the collar 72 may be adjusted along the extension 69 of the draw bar in such a manner as to 60 actuate the stop mechanism when the lifter rail is partially elevated so that when the new bobbin is wound a partial traverse of

winding will be wound downwardly before 65 the first full upward traverse is laid. It therefore follows that when the bobbin is unwound in the shuttle the feeler finger of the loom will enter the slot in the bobbin and institute the operation of the replenishing mechanism while there are two partial windings upon the bobbin which is ample to supply a pick for an exceptionally wide loom.

Having fully described my invention, 75 what I claim as new and desire to secure by Letters Patent is:

1. In a spinning machine having a series of bobbin spindles, means for rotating the bobbins thereon, a lifter rail and means for 80 actuating the same including builder mechanism for causing a traverse of yarn upon the bobbin, stop mechanism comprising means automatically operable during the downward movement of the traverse of the yarn 85 upon the bobbin to stop the machine to retain said lifter rail at a predetermined point of the traverse of the yarn upon the bobbin well below the highest point of traverse and means for restoring the builder 90 mechanism to starting position without altering the position of traverse whereby the first full layer of filling laid upon the bobbin will be wound from the bottom upwardly. 95

2. In a spinning machine having a series of bobbin spindles, means for rotating the bobbins thereon, a lifter rail and means for 100 actuating the same including builder mechanism for causing the traverse of yarn upon the bobbin, stop mechanism comprising adjustable means automatically operable during the downward movement of the traverse of the yarn upon the bobbin to stop the machine to retain said lifter rail at a predetermined point of the traverse of the yarn upon the bobbin below the highest point of traverse and means for restoring the builder 105 mechanism to starting position without altering the position of traverse whereby the first full layer of filling laid upon the bobbin will be wound from the bottom upwardly. 110

3. In a spinning machine having a lifter rail, a series of bobbins mounted thereon, 115 means for rotating the bobbins, builder mechanism for actuating said lifter rail, stop mechanism comprising means automatically operable to stop the machine to retain said lifter rail at the lowest point of 120 traverse of the yarn upon the bobbin, means for restoring the builder mechanism to starting position without altering its position of traverse, whereby the first layer of filling laid upon the bobbin will be wound 125 from the bobbin upwardly.

4. A spinning machine having a series of bobbins, a lifter rail and means for

actuating the same including traverse controlling mechanism, stop mechanism comprising a weight actuated belt shifting mechanism, means adapted to be operated by the 5 traverse controlling mechanism during the downward traverse of the yarn upon the bobbin to release said weight mechanism to stop the machine with the lifter rail at a point intermediate of the limits of traverse 10 of the yarn upon the bobbin and means for restoring the lifter rail actuating mechanism to starting position without altering the position of the rail in respect to the point of traverse upon the bobbin at which it is arrested.

5. In a spinning machine having a series of bobbin spindles, means for rotating bobbins thereon, a lifter rail and means for actuating the same, stop mechanism operated by 20 the traverse controlling mechanism to stop said actuating mechanism to retain said lifter rail at a predetermined elevation comprising a weight actuated belt shifting mechanism, a latch adapted to support said 25 weight and to release the same to actuate said belt shifting mechanism, a draw bar provided with a collar connected to said latch, a detent carried by said traverse controlling mechanism adapted to engage said 30 collar to release said latch from engagement with said weight, whereby upon the descent of the weight the belt will be shifted from a tight to a loose pulley and means actuated by the falling weight to release said detent.

35. 6. In a spinning machine having a series of bobbin spindles, means for rotating bobbins thereon, a lifter rail and means for actuating the same, stop mechanism operated by the traverse controlling mechanism to stop 40 said actuating mechanism to retain said lifter rail at a predetermined elevation comprising a weight actuated belt shifting mechanism, a latch adapted to support said weight and to release the same to actuate 45 said belt shifting mechanism, a draw bar having a collar adapted to have a restricted sliding movement connected to said latch, a detent carried by said traverse controlling mechanism adapted to engage said collar to 50 release said latch from engagement with said weight, and means operated by said belt shifting mechanism to disengage said detent from said collar.

7. In a machine of the class described, 55 stop mechanism releasing and actuating means comprising a draw bar having an adjustable collar adapted to be engaged by a moving member of said machine at a predetermined time in the cycle of operation thereof, whereby the machine may be arrested with the elements thereof in predetermined relative position and means to release 60 said member automatically upon the initiation of the operation of the stop mechanism.

8. In a machine of the class described stop 65 mechanism releasing and actuating means comprising a draw bar having an offset portion, provided with means adapted to be engaged by a moving member of said machine at a predetermined time in the operation 70 thereof, means connected to said draw bar adjacent to said offset adapted to be actuated by the operation of said releasing means to raise the main portion of said draw bar and thereby lower the offset portion thereof, 75 whereby the latter will be released from its engagement with said moving member.

9. In a spinning machine having a series of bobbin spindles, means for rotating the bobbins thereon, a lifter rail, means for actuating the same including a builder arm, a carriage actuated thereby and means connecting said carriage to said lifter rail, a screw connecting said builder arm and said carriage, means for rotating the screw progressively upon each reciprocation of the builder arm, a detent upon said carriage, stop mechanism including a latch having a member extending substantially parallel to said screw, a collar upon said latch adapted 90 to be engaged by said detent to release the stop mechanism at the highest point of traverse on said lifter rail and means actuated by said stop mechanism to release the detent from the collar upon said latch. 95

10. In a spinning machine having a series of bobbin spindles, means for rotating the bobbins thereon, a lifter rail, builder mechanism for operating the same comprising a lever, a carriage connected to said lifter rail 100 and a screw connecting said builder lever with said carriage, means for actuating said screw progressively to vary the position of the traverse, a cam adapted to actuate said lever, and stop mechanism automatically operable by an instrumentality upon the said carriage to arrest the machine and to retain the same in arrested position at a predetermined point of contact between said cam and said builder lever whereby the lifter 105 rail will be positioned at a point below the highest point of traverse of the yarn upon the bobbin, and means for returning the builder mechanism to initial position without varying the position of the cam relative 110 to the builder lever.

11. In a spinning machine having a lifter rail, a series of bobbins mounted thereon, means for rotating the bobbins, caps for said bobbins, builder mechanism for operating 120 the same comprising a lever, a carriage connected to said lifter rail and a screw connecting said builder lever with said carriage, means for actuating said screw progressively to vary the position of the traverse, a cam 125 adapted to actuate said lever and stop mechanism automatically operable by a pawl upon said carriage to arrest the machine

and to retain the same in arrested position when the apex of the cam is in contact therewith and means for returning the builder mechanism to initial position without varying the position of the cam relative to the builder lever.

In testimony whereof, I have signed my

name to this specification in the presence of two subscribing witnesses.

AMARIAH AVERY.
